LIGHTING SYSTEM

Arnold A. Bluemle and William Earl Brown, Anderson, Ind., assignors to General Motors Corporation, Detroit, Mich., a corporation of Delaware

Application April 4, 1941, Serial No. 336,916

9 Claims. (Cl. 171—97)

This invention relates to electric lighting circuits, particularly for automobile use. It has been the practice to protect the automobile head lamp circuits by single overload circuit breakers such as a fuse or a bi-metallic switch. In such installation if one head lamp circuit is overloaded due to accidental grounding, then both head lamps are extinguished when the fuse blows out.

It is an object of the present invention to provide for a separated fusing to the head lamp circuits while at the same time providing for dimming the head lamps by the use of a single dimmer switch unit.

A further object of the invention is to provide for automatically switching to another head lamp circuit when one of the head lamp circuits blows out, for example, if one of the light filaments of a head lamp blows out then the dim filaments of both head lamps will burn. While automatic switching of filament circuits is perhaps an old expedient it is believed to be novel in combination with the separate fusing of the head lamp circuits and with the use of a single dimmer switch unit.

Further objects and advantages of the present invention will be apparent from the following description, reference being had to the accompanying drawing wherein preferred embodiments of the present invention are clearly shown.

In the drawing:

Figs. 1, 2, 3 and 4 are wiring diagrams illustrating different embodiments of the present invention.

In all of the figures numeral 20 designates the head lamp having bright or main beam filaments 21 and dim or depressed beam filaments 22. Numerals 23 indicate the parking lamps and 24 is the tail lamp. In each of the figures a battery 25 which is grounded is connected with terminals 26 and 27 of a lighting switch 28. Switch 28 includes a movable contact 29 movable from an "off" position 29' shown in dot-dash lines to "on" position in full lines wherein it bridges contacts 30 and 31. Contact 30 is connected with terminal 26 by fuse or other overload protecting device 32. Switch 28 includes another movable contact 33 having an "on" position shown in full lines wherein it bridges contacts 34, 35, and 36 and having an intermediate "on" position indicated by dot-dash line 33' wherein it breaks contacts 36 and 37. Contact 34 is connected with terminal 27 by fuse or other overload protector 38. Contact 36 is connected by a wire 39 with tail lamp 24. Contact 37 is connected by wires

40 and 41 with parking lamp 23. In Fig. 4, the switch 28 has a contact 42 connected by strap 43 with contacts 34.

The movable contacts 29 and 33 of switch 28 are connected to a single operating member 28a. Contacts 29 and 33 have a full "off" position to the left of the dot-dash-line positions shown, an intermediate position shown in dot-dash lines and full "on" position shown in full lines.

In Fig. 1 the head lamps are dimmed by individual switches 50 contained in a single housing and operated by a single member 50a. The dimmer 50 comprises movable contacts 51 each in the form of an equi-lateral triangle and each operable to bridge contacts 52 and 53 in one position of the movable contact and contacts 54 and 55 in the next position. Contacts 52 and 54 are connected by strap 56. When contacts 52 and 53 are connected by the movable contact 51 as shown in full lines, the head lamp bright filaments 21 will be connected by battery 25 thru movable switch contact 29 shown in full "on" position and by the fuse 32. Similarly the left hand head lamp is connected by contacts 51 of the dimmer switch and by contact 33 in the full "on" position and by the fuse 32. When the two movable contacts 51 of the dimmer switch unit are moved into the dot-dash line position 51', the head light dim or depressed beam filaments 22 will be connected to the battery by fuses 32 and 38, respectively. The lighting system shown in Fig. 1 provides separate fuse protection for each head lamp. If the right hand head lamp should become overloaded and fuse 32 should melt, the left hand head lamp will remain operative.

In the circuit shown in Fig. 2, the bright or high beam filaments 21 of the two head lamps 20 are connected in parallel and both in series with a dimmer switch 60 and with one of the fuses. Similarly the bright or low beam filaments 22 of the two head lamps are connected in parallel and both in series with the switch 60 and one of the fuses. If one of the fuses blows out both lamps cease burning until the foot dimmer switch 69 is operated to turn on the other set of filaments. Switch 60 comprises stationary contacts 61 connected with contact 35 of switch 28, a contact 62 connected with the head lamp dim beam filaments 22, a contact 63 connected with the high lamp bright beam filaments 21, and a contact 64 connected with contact 31 of switch 28. Dimmer switch 60 includes a movable contact 65 in the form of equi-lateral triangle and adapted to bridge contacts 61 and 63

in one position shown in full lines, and contacts 62 and 64 in the dot-dash position 65'. When contact 65 is in the full line position the bright beam filaments 21 are connected to the dimmer switch contact 65 and thru the main switch contact 33 and fuse 38 with the battery. If the fuse 38 should blow out both head lamp filaments 31 will cease to burn. Then if the dimmer switch contact 65 is moved into position 65' the head lamp dim filaments 22 will burn since they are connected with the battery thru the dimmer switch 60, contact 29 of switch 28, and fuse 32.

The lighting system shown in Fig. 3 provides separate fusing of the high beam circuit and of the low beam circuit of the head lamp as of Fig. 2 and also for automatically switching from the high beam circuit to the low beam circuit in case the fuse blows out in the high beam circuit. In Fig. 3 the dimmer switch 70 does not directly control the head lamp filament circuits but indirectly thru a relay 80. Switch 70 comprises an insulated contact 71 and a grounded contact 72 to be bridged by movable contact when in the full line position 73 or to be disconnected when the movable contact is in the position 73'. Relay 80 comprises a frame 81 supporting a core 82 surrounded by a coil 83 grounded on the frame which is connected by wire 84 with contact 31 of switch 28. The other end of coil is connected by wire 85 with dimmer switch contact 71. Frame 81 carries an armature hinge 86 supporting an armature 87. Armature 87 carries contact 88 for engaging contact 89 connected by wire 90 with the two bright filaments 21. Armature 87 insulatingly supports a contact 91 connected by wire 92 with contact 35 of switch 28. Contact 91 normally engages contact 93 connected with dim filaments 22. When the contact 73 of dimmer switch 70 is in the "on" position (shown in full lines) the relay coil 83 will be connected with the battery through the contact 29 of switch 28 and fuse 32. The armature 87 will be pulled down to close contacts 88, 89 thereby connecting the head lamp bright filaments 21 with the battery thru fuse 32. If fuse 32 should blow relay coil 83 will be disconnected from the battery and armature 87 will move upwardly to separate contact 88 from contact 89 and to bring contact 91 into engagement with contact 93 thereby connecting the head lamp dim filaments 22 with the battery thru contact 33 of switch 28 and fuse 38. If fuse 32 does not blow but the driver wishes to dim the head lamp, he moves the dimmer switch contact 73 to dot-dash line position 73a thereby disconnecting relay coil 83 from the battery whereupon the dim filaments 22 are connected with the battery.

Fig. 4 provides for fuse protection as in Figs. 2 and 3 and also for automatically switching on the dim filament circuit in case the bright filament circuit is interrupted, and for switching on the bright filament circuit in case the dim filament circuit is interrupted. For this purpose there is provided a relay 100 having a core 101 surrounded by two magnet coils 102 and 103 wound in such manner that, when both are energized, the magnetic effect of one operates the magnetic effect of the other so that the relay armature 104 is not attracted toward the core. Armature 104 which is connected with the bright filaments 21 carries a contact 105 normally separated from contact 106 connected with one end of relay coil 102 and with a wire 107 connected with contact 35 of switch 28. Armature 104 in-

sulatingly supports a contact 110 normally engaging a contact 111 connected with dim filaments 22. Contact 110 is connected by wire 112 with contact 31 of switch 28 and by wire 113 with relay coil 103 connected by wire 114 with contact 116 of dimmer switch 115. Switch 115 includes grounded stationary contacts 117 and 118 connected by strap 119, and also stationary contacts 120 and 121 connected by strap 122 and by wire 123 with relay coil 102. Dimmer switch 115 comprising a triangle shaped movable contact having a full line 124 and dot-dash line position 124'. When it is desired to burn the head lamp bright the dimmer switch 115 is actuated so that its movable contact is in the full line position 124. The following circuit is completed: battery 25, terminal 27, fuse 38, contact 33 of switch 28, wire 107, relay coil 102, wire 123, contact 121, contact 124, contact 118, and ground to battery. Under these conditions the relay coil 103 is not energized; therefore coil 102 alone is effective and it causes the armature 104 to move downwardly to connect contacts 105 and 106, and to cause the head lamp bright filaments 21 to be connected with the battery thru the contact 33 of switch 28 and fuse 38. When it is desired to dim the head lamp the switch 115 is actuated so that its movable contact comes into the position 124' whereby both coils 102-103 of relay 100 are caused to be connected with the battery 125. Since both coils 102-103 are energized at the same time and since they produce magnetism of opposite polarity, there is no attraction of armature 104 downwardly; and contact 110 remains in its position of normal engagement with the contact 111. Therefore the dim filaments 22 are both connected with the battery 25 thru the switch contact 29 and fuse 32.

Assume that the dim filament circuit becomes overloaded and fuse 32 blows out. Then relay coil 103 is disconnected from the battery but coil 102 remains connected with the battery. Therefore armature 104 moves downwardly to cause contact 105 to engage contact 106 thereby connecting the bright filaments with the battery.

Assume that both fuses are operative and that the dimmer switch 115 has been actuated to cause the head lamp bright filaments 21 to be connected with the battery as the result of moving contact of switch 115 to the full line position 124. As stated before such operation of the dimmer switch causes relay coil 102 to be connected with the battery to cause contacts 105 and 106 to engage. In case fuse 38 in the bright filament blows out, relay 102 will become deenergized and the armature 104 will be released and contacts 105 and 106 will be separated and contacts 110 and 111 will engage. Then the head lamp dim filaments 22 will be connected with the battery.

From the foregoing description of the construction and method of operation of various embodiments of the present invention it is apparent that I have provided for the control of the bright and dim filaments of the head lamps and also for the separate fusing of the head lamps as in Fig. 1 and for the separate fusing of the bright and dim filament circuits as in Figs. 2, 3 and 4. As shown in Figs. 3 and 4, I provide also for the automatic switching from bright to dim filaments in case the fuse of the bright filament circuit blows. In Fig. 4 I provide not only for automatic switching from bright to dim in case the fuse of the bright filament circuit blows out, but also for automatic switching from dim to bright in

case the fuse of the dim filament circuit blows out.

While the embodiments of the present invention as herein disclosed, constitute a preferred form, it is to be understood that other forms might be adopted, all coming within the scope of the claims which follow.

What is claimed is as follows:

1. An automobile lighting system comprising a current source, head lamps having high beam or bright filaments and low beam or dim filaments, a plurality of switches for connecting the source with the lamps and for distributing current to the filaments in groups, thermal circuit breakers connected in parallel and each in series with one of the switches for protecting the groups of filaments, and means connected between the filaments and the switches for selectively effecting the connecting of the bright or the dim filaments with the current source.

2. An automobile lighting system comprising a current source, head lamps having high beam or bright filaments and low beam or dim filaments, a mechanically connected pair of switches adapted to be operated in one position for connecting the source with the lamps and for distributing current to the filaments in groups, thermal circuit breakers arranged in parallel with respect to each other and each in series with the source and one of said switches for protecting the groups of filaments, means connected between both switches and both filaments for selectively connecting the bright or the dim filaments with the current source, and means for automatically switching to another group of filaments in case the circuit of one group becomes interrupted.

3. An automobile lighting system comprising a current source, head lamps having high beam or bright filaments and low beam or dim filaments, a pair of switches operable in unison and arranged in parallel with respect to each other for connecting the source with the lamps and for distributing current to the bright filaments as a group and to the dim filaments as a group, thermal circuit breakers arranged in parallel with respect to each other and each in series with the source and one of the switches for protecting the groups of filaments and means for selectively effecting the connection of the bright or the dim filaments with the current source.

4. An automobile lighting system comprising a current source, head lamps having high beam or bright filaments and low beam or dim filaments, a pair of switches for connecting the source with the lamps and for distributing current to the bright filaments as a group and to the dim filaments as a group, thermal circuit breakers connected in parallel and each in series with the source and one of said switches for protecting the groups of filaments, means for selectively effecting the connection of the bright or the dim filaments with the current source and means for automatically switching from the bright filament circuit to the dim filament circuit in case

the bright filament circuit becomes interrupted.

5. An automobile lighting system comprising a current source, head lamps having high beam or bright filaments and low beam or dim filaments, a mechanically connected pair of switches adapted to be operated in one position for connecting the source with the lamps and for distributing current to the bright filaments as a group and to the dim filaments as a group, thermal circuit breakers connected in parallel and each in series with the source and one of said switches for protecting the groups of filaments, means for selectively effecting the connection of the bright or the dim filaments with the current source, and means for automatically switching from the bright filament circuit to the dim filament circuit in case the bright filament circuit becomes interrupted and for automatically switching from the dim filament circuit to the bright filament circuit in case the dim filament circuit becomes interrupted.

6. A system according to claim 4 in which said automatic switching means includes a relay having a magnet coil whose connection with the source is controlled by the means for selectively effecting the connection of the bright or dim filaments with the current source.

7. A system according to claim 5 in which said automatic switching means includes a relay having magnet coils of opposite polarity and in which the connection of one or both of said magnet coils with the source is controlled by the means for selectively effecting the connection of the bright or dim filaments with the current source.

8. An automobile lighting system comprising a current source, a head lamp having a bright filament and a dim filament; an independent switch for each filament, thermal current circuit breakers connected in parallel and each in series with the source and one of the independent switches; selective switch means associated with both of the independent switches and both of the filaments, said selective switch means effecting the optional connecting of the bright filaments or the dim filament with the current source.

9. An automobile lighting system comprising a current source, a head lamp having a bright filament and a dim filament; an independent switch for each filament, thermal current circuit breakers connected in parallel and each in series with the source and one of the independent switches; selective switch means associated with both of the independent switches and both of the filaments, said selective switch means effecting the optional connecting of the current source with the bright filament through one of the severally connected thermal current circuit breakers and independent switches in one position and the connecting of the dim filament through another of the severally connected thermal current circuit breakers and independent switch in another position.
